UNITED STATES PATENT OFFICE.

KENNETH J. UNWIN, OF SHREWSBURY, MASSACHUSETTS, ASSIGNOR TO CROMPTON & KNOWLES LOOM WORKS, OF WORCESTER, MASSACHUSETTS, A CORPORATION OF MASSACHUSETTS.

COMBINED LATCH AND WEFT DETECTOR FOR LOOM TRANSFERRERS.

Application filed July 21, 1926. Serial No. 124,044.

This invention relates to improvements in weft detectors of the type mounted on regularly moving transerrer arms and it is the principal object of the invention to simplify 5 the mechanism intermediate the detector and the replenishing mechanism to the end that a minimum number of parts may be employed.

Patent No. 1,372,316 to Ryon shows a 10 loom having a regularly moving transerrer arm with a weft detector supported thereon, the detector being presented to the surface to be detected on alternate beats of the loom by a downward movement of the 15 transerrer arm. In co-pending application Ser. No. 78,181 filed by Hume there is shown a somewhat similar mechanism wherein the indicating plunger is normally held in locked position by a latch pivoted 20 on the transerrer arm, the latch being movable to unlocking position at the time of weft exhaustion by engagement with the detector. In the Hume construction the detector is mounted on a lever pivoted to 25 the transerrer arm and is out of contact and independent with respect to the latch at all times except when an indication of weft exhaustion is being given. It is a further object of my invention to combine the latch 30 and detector and give these two devices a common support.

It is a further object of my invention to provide a side slip weft detector movably mounted with respect to the latch and deriving 35 its operative movement from the energy stored therein due to its downward movement by the transerrer arm. In this respect my present invention embodies certain features set forth in co-pending application Ser. No. 120,491 filed by Turner.

With these and other objects in view which will appear as the description proceeds, my invention resides in the combination and arrangement of parts hereinafter 45 described and set forth in the claims.

In the accompanying drawings wherein I have shown a convenient embodiment of my invention,

Fig. 1 is a vertical section through that 50 portion of the transerrer arm which normally lies over the shuttle and bobbin and showing my invention in the position it as-

sumes when contacting with a sufficient supply of weft,

Fig. 2 is a view similar to Fig. 1 but 55 with the detector shown in indicating position with insufficient weft present,

Fig. 3 is a detail top plan view of a 60 portion of the transerrer arm looking in the direction of arrow 3, Fig. 2, and

Fig. 4 is a detail section on line 4-4 of Fig. 2.

Referring to the drawings it will be seen that I have provided a transerrer arm 10 having a portion 11 which extends over and substantially parallel to the bobbin and shuttle when the latter is boxed. A controller plunger 12 is slidably mounted in the portion 11 and has a shoulder 13 which receives the inward thrust of a compression spring 14 the outer end of which bears against that part of portion 11 which defines the left hand end of a chamber 15 as viewed in Fig. 1 in which the plunger moves. Said plunger has a reduced end 16 70 provided with a pin 17 which engages a part of the transerrer arm to limit right hand movement of the plunger and said reduced end is provided with a notch 18 and a head 19. 80

A latch 20 having a hooked end 21 to enter the notch 18 is pivoted on a pin 22, the parts normally being in the position shown in Fig. 1 with the hook 21 holding the plunger 12 so that the right hand end of the 85 latter is substantially flush with the adjacent face of the transerrer arm. Said arm is moved downwardly toward the bobbin B on detecting beats of the loom by mechanism not shown but well understood 90 in the art and being substantially the same as shown in the aforesaid patent. The matter thus far described is old and forms no part of my invention.

In carrying my improvements into effect 95 I provide the latch 20 with a groove 30 diagonally disposed as shown in Fig. 1 and I further provide the latch with a plate 31 riveted or otherwise secured to the latch to define with the groove 30 a slot to receive 100 the upwardly extending shank 32 of a weft detector 33 provided with weft engaging teeth 34. An extension 35 of the detector has secured thereto the lower end of a ten-

sion spring 36 the upper end of which is held to a wall 37 of the transferrer arm.

Under normal conditions the parts are in the position indicated in dotted lines in Fig.

5 1, the spring 36 holding the detector 33 in raised position and serving also to hold the hook 21 in the notch 18. On each downward movement of the transferrer arm 10 the latter is brought to a sudden stop but the detector, 10 being free to slide on the latch against the action of comparatively light spring 36, will continue to move toward the yarn on the bobbin after the transferrer has come to rest. When sufficient yarn is present the teeth 34 15 will be embedded therein and further movement of the detector will be prevented. When insufficient weft is present, however, the detector, upon striking a bare bobbin, will continue its downward movement and 20 slide along the bare bobbin, as is indicated in Fig. 2, this motion resulting in an angular movement of the latch about the pin 22. The hook 21 is therefore raised and the spring 14 will move the plunger 12 to the position indicated in Fig. 2 which, as set forth in the aforesaid patent to Ryon, corresponds to an 25 indicating movement to initiate replenishment as the transferrer arm ascends. Immediately after the indicating movement has 30 been completed the spring 36 will tend to restore the detector to the position indicated in Fig. 1 and will also act to create a slight pressure between the hook 21 and the head 19 so that as the plunger 12 is moved 35 to the left on the ascending movement of the transferrer arm as is set forth in the aforesaid patent to Ryon said hook will enter the notch 18.

From the foregoing it will be seen that I 40 have provided a very simple weft detector depending for its actuation on the energy stored in a moving part and having but one spring which serves not only to return the detector to normal position but also insures 45 proper co-action between the latch and the plunger 12. It is to be understood that the detector may be made of any approved material such as will reduce friction to a minimum as the detector slides on the latch. It 50 will further be seen that I have provided a combined detector and latch which is connected to the transferrer arm by a single means of support, namely, the pin 22.

Having thus described my invention it 55 will be apparent that changes and modifications may be made therein by those skilled in the art without departing from the spirit and scope of the invention, and I do not wish to be limited to the details herein discussed but what I claim is:

1. In a weft detector for a loom having a transferrer arm receiving a regular movement at periodic intervals toward a weft surface to be detected, a controller on the 60 transferrer arm, a latch normally holding

the controller in inoperative position, and a weft detector mounted on the latch and having an operative movement each time the transferrer arm moves toward the surface to be detected and tending to move the latch to a position to release the controller. 70

2. In a weft detector for a loom having a transferrer arm receiving a regular movement at periodic intervals toward a weft surface to be detected, a controller on the trans- 75 ferrer arm, resilient means tending to move the controller to operative position, a latch movably mounted on the transferrer arm and operatively related to the controller to hold the latter normally in inoperative position, and a weft detector movably mounted on the latch and having a movement on each detecting beat of the loom tending to move the latch to controller releasing position, said detector being restrained from moving the 80 latch when sufficient weft is present and being operative to give the latch a releasing movement when insufficient weft is present. 85

3. In a weft detector for a loom having a transferrer arm receiving a regular move- 90 ment at periodic intervals toward a weft surface to be detected, a controller on the trans- ferrer arm, a latch normally holding the controller in inoperative position, a weft detector slidably mounted on the latch and dis- 95 posed obliquely with respect to the surface to be detected, said detector tending to move the latch to controller releasing position on each movement of the transferrer arm toward the surface to be detected, releasing 100 movement being prevented when the detector engages a sufficient supply of weft and the detector sliding along a substantially ex- 105 hausted bobbin to give movement to the latch to cause the latter to release the controller. 110

4. In a weft detector for a loom having a transferrer arm receiving a regular move- 115 ment at periodic intervals toward a weft surface to be detected, a controller on the trans- ferrer arm, a latch pivoted to the trans- 120 ferrer arm and having a hooked portion to cooperate with a notch in the controller, a weft detector slidably mounted on the latch and having a pivotal movement with the lat- 125 tcher, and a single resilient means interposed between the detector and the transferrer arm tending to hold the hooked part of the latch in the notch of the controller and tending also to hold the detector in normal position, 130 said detector moving toward the surface to be detected each time the transferrer is presented to the surface to be detected, said detector being restrained against movement about the pivot of the latch when sufficient weft is present and moving along the surface of a substantially denuded bobbin to move the latch pivotally to cause the hooked part of said latch to move out of the notch in the plunger and release the latter. 135

5. In a weft detector for a loom having a transerrer arm receiving a regular movement at periodic intervals toward a weft surface to be detected, a controller on the 5 transerrer arm, a latch normally holding the controller in inoperative position, a detector slidably mounted on the latch, resilient means connected to the detector and tending to preserve locking engagement between the latch and the controller and also 10 serving to hold the detector yieldingly in normal position, and a pivotal connection between the latch and the transerrer arm, said detector tending to move the latch about the 15 pivot of the latter to release the controller each time the transerrer arm is moved toward the surface to be detected, the detector being prevented from having such motion when sufficient weft is present and said detector 20 moving angularly about the pivot of the latch and moving the latter to controller releasing position when insufficient weft is present.

6. In a weft detector for a loom having a transerrer arm receiving a regular movement at periodic intervals toward a weft surface to be detected, a controller on the transerrer arm, a latch for the controller normally holding the latter in inoperative 25 position, and a detector slidably mounted on the latch and yieldingly held away from the surface to be detected, said detector being obliquely disposed with respect to the surface to be detected and tending to move relatively to the latch after the transerrer arm has come to rest in its movement toward the surface to be detected by reason of the energy stored in the detector due to the movement of the transerrer arm, said detector 30 when engaging a sufficient supply of weft being restrained against movement in the direction of the length of the surface to be detected but said detector when engaging a substantially exhausted surface moving

along the latter to impart movement to the latch to move the same relatively to the controller and release the latter.

7. In a weft detector for a loom having a transerrer arm receiving a regular movement at periodic intervals toward a weft 50 surface to be detected, a controller on the transerrer arm, a latch to hold the controller normally in inoperative position, a detector mounted on and movable with respect to the latch in a direction toward and 55 from the surface to be detected, said detector tending to move toward the surface to be detected by reason of the energy stored therein after the transerrer arm has come to rest in its movement toward the surface 60 to be detected, the detector being arrested in movement along the surface when sufficient weft is present to impart movement to the latch to cause the latter to release the plunger, and a single resilient means operatively connected to the detector and acting to restore the latter to normal position and 65 also to preserve holding engagement between the latch and the controller.

8. In a weft detector for a loom having a 70 transerrer arm receiving a regular movement at periodic intervals toward a weft surface to be detected, a controller on the transerrer arm, a latch normally holding the controller in inoperative position, a 75 weft detector mounted on the latch and having an operative movement each time the transerrer arm moves toward the surface to be detected and tending to move the latch to a position to release the controller, 80 and a single resilient means connected to the detector and serving to move said detector to normal position and also preserve holding engagement between the latch and controller.

In testimony whereof I have hereunto affixed my signature.

KENNETH J. UNWIN.
